UNITED STATES PATENT OFFICE.

NELLIE PARK ANDERSON, OF CHICAGO, ILLINOIS.

DUPLICATING-MACHINE.

SPECIFICATION forming part of Letters Patent No. 544,648, dated August 20, 1895.

Application filed April 6, 1895. Serial No. 544,724. (No model.)

To all whom it may concern:

Be it known that I, NELLIE PARK ANDERSON, a citizen of the United States, residing at Chicago, in the county of Cook and State 5 of Illinois, have invented a certain new and useful Improvement in Duplicating-Machines, (Case No. 1,) of which the following is a full, clear, concise, and exact description, reference being had to the accompanying drawings, forming a part of this specification.

My invention relates to a machine for duplicating copies of type-written or other matter, and my object is to provide means for 15 automatically moving the frame carrying the stencil and the ink-roller, whereby it is only necessary for the operator to place the sheets upon which the copies are to be made in the machine and to remove the same therefrom.

20 In the art of duplicating type-written or other matter it is the custom to provide a wax sheet, upon which the matter is written by means of a type-writer or by a stylus-pen, thus producing raised letters upon the wax sheet. The wax sheet thus forms the stencil, which is laid upon the sheet of paper upon which the copying is to be made with the raised letters in contact with the sheet. An 25 ink-roller is then moved over the back of the stencil, thus saturating the same with ink, the ink coming in contact with the sheet of paper where the raised letters rest in contact therewith, thus producing the copy upon the sheet of paper. The sheet of paper is then 30 removed and a new sheet is placed in position, after which the operation is repeated.

A duplicating press or machine of the general type of the invention herein is described in Letters Patent No. 238,956, dated March 15, 40 1881, a stencil-frame being provided adapted to be raised and lowered, an ink and presser roller being provided adapted to be passed over the back of the stencil-sheet to ink the same and to press the same against the sheet 45 to be printed, the roller being moved back in contact with the stencil-sheet. I have found that when the roller is thus moved in both directions over the stencil-sheet the printed sheet is blurred, and the object of the present 50 invention is to provide a machine in which the roller is moved out of contact with the stencil-sheet while moving in one direction.

A further object of the invention is to provide means for raising and lowering the stencil-frame, so that the stencil-sheet will be 55 gently lowered into contact with the sheet to be printed.

I will describe my invention by reference to the accompanying drawings, in which—

Figure 1 is a plan view of the machine embodying my invention. Fig. 2 is a sectional view on line 2 2, Fig. 1. Fig. 3 is a side elevation of the machine. Fig. 4 is a view of a modification of my invention. Fig. 5 is a front elevation of the machine. Fig. 6 is a 65 longitudinal section of the machine, a portion of the frame being broken away. Fig. 7 is a detail view illustrating the device for throwing the roller-operating mechanism out of gear. Fig. 8 is a detail view of a portion of 70 the brake mechanism.

Like letters refer to like parts in the several figures.

Upon the table A of the machine is provided a frame A', provided with hinges A², whereby 75 the frame may be rocked about one end. The frame is adapted when horizontal to surround a projecting plate A³, provided upon the table A of the machine. Upon the frame A' is provided a rectangular groove A⁴, within which 80 a rectangular iron frame B is adapted to fit, the face of the frame B lying flush with the face of frame A' when in position. Clamps B' are provided upon the frame A' adapted to hold the frame B in position. 85

The stencil C carrying the raised letters is placed upon the frame with the raised letters extending downward and is clamped at the edges between the frame B and the walls of the groove A⁴, and the sheet of paper D upon 90 which the copy is to be made is placed upon the face of plate A³, being thus in contact with the raised letters of the stencil.

Opposite the hinged end of the frame A' is provided an ink-plate E, upon which the ink 95 is adapted to be spread. An ink-roller E' is adapted to be rolled over the surface of the ink-plate and over the top of the stencil C. The stencil is thus saturated with ink and is pressed against the sheet of paper D by the 100 passage of the ink-roller, thus producing the imprint upon the paper corresponding to the raised letters provided on the stencil. The roller E' is then raised and carried back to

its former position upon the ink-plate, and the frame A' is rotated about its hinged end, the sheet D being removed and a new sheet placed in position, after which the operation 5 is repeated.

Upon the frame of the machine is provided a pedal F, connected by means of rod F' with a crank F², mounted upon a shaft G. The shaft G carries upon its opposite end a fly-wheel F³ and a pulley F⁴, whereby power may be applied by means of a belt. Upon the shaft G is mounted a pinion G', adapted to mesh with the gear-wheel G², mounted upon the shaft G³. Upon the shaft G³ is mounted 10 an eccentric H, the strap H' of which is connected by means of the connecting-rod H² with the cam H³, pivoted at H⁴ to the frame of the machine. The cam H³ is adapted when rotated to engage frame A' and raise the 15 same to the position illustrated in Fig. 3, thus permitting the removal of the printed sheet and the placing of a new sheet in position. As the eccentric continues its movement the cam is rotated to permit the frame to descend. 20 The gear-wheel K is adapted to mesh with the gear-wheel G² and is mounted upon shaft K', supported in the frame of the machine. Upon the gear-wheel K is provided a crank-pin K², connected by means of a rod K³ with 25 the lever L, pivoted at L'. The lever L is made in two parts—a short lever L² pivoted upon the outside of the frame and a long lever L³ pivoted to the inside of the frame of the machine—the two parts being joined together 30 by a bolt or pin L⁴, which is adapted to work in a slot L⁵ provided in the frame of the machine. In the end of the lever L is provided a longitudinal slot L⁶, adapted to engage the shaft E² of the ink-roller E'. A similar lever is provided upon each side of the 35 machine, the levers being connected by a cross-piece. As the gear-wheel K is rotated the lever L is rotated upon its pivot, thus carrying the ink-roller forward and causing it to move over the stencil C, the ink-roller being journaled loosely upon its shaft. Upon the shaft 40 of the ink-roller is provided a pinion E³, adapted as the roller is moved forward to engage the teeth upon a rack or guide bar M. The guide-bar M is pivoted at M' and carries 45 pins M² M³, adapted to move in the slots M⁴ M⁵. To one of the pins M² is attached a spring M⁶, adapted to draw the free end of the guide-bar downward. As the roller thus moves forward 50 it is pressed down upon the stencil with the desired force through the agency of the guide-bar M and the spring M⁶. When the roller has passed the free end of the guide-bar M, the spring M⁶ draws down the free end 55 of the guide-bar, so that as the roller moves back it travels over the top of the guide-bar M, being thus raised above the surface of the stencil. The ink-roller is thus prevented from moving over the surface of the stencil 60 on its return stroke.

Instead of providing teeth upon the under

side of guide-bar with which the pinion E³ may engage, I may provide teeth upon the table beneath the pinion, as illustrated in Fig. 4. While it is desirable that the teeth 70 be provided upon the upper side of the guide-bar these teeth may be omitted, but the operation is not so effective as when they are present. The essential function of the guide-bar M is to raise the ink-roller above the stencil on its return stroke. It is necessary that the ink-roller remain upon the ink-plate while the frame carrying the stencil is being raised and lowered, and for this purpose any means may be employed for disconnecting the mechanism that drives the roller from the continuously rotating parts. I have illustrated mechanism for this purpose whereby the gear-wheel K is adapted to be moved out of engagement with the gear-wheel G². The shaft 80 K', upon which the gear-wheel K is mounted, is journaled in slots K⁴, which permit a slight upward excursion of the shaft. Upon the shaft K', by the side of gear-wheel K, is provided a cam-wheel K⁵, carrying a concentric groove K⁶, provided with a notch K⁷ at one point in the circumference. The end of rod N' is adapted to extend into the groove K⁶. Upon the strap H' of the eccentric H is mounted an arm O, adapted as the eccentric 90 rotates to engage the shaft K', and thus elevating the same. The arm O engages the shaft at a time when the notch K⁷ of the groove K⁶ is opposite the rod N', so that the rod N' enters the notch K⁷, thus bringing the shaft K' to 100 rest. The raising of the shaft K' thus disengages the gear-wheel K from the gear-wheel G². As the eccentric continues its rotation, the arm O is lowered, thus bringing the gear-wheel K into engagement with the gear-wheel 105 G² and advancing the ink-roller. The gear-wheel K is thus moved out of engagement with gear-wheel G², maintaining the ink-roller at rest during the time the frame carrying the stencil is being raised and lowered. 110

Having described my invention, what I claim as new, and desire to secure by Letters Patent, is—

1. In a stencil duplicating machine, the combination with a plate upon which the sheet 115 to be printed is laid, of a frame carrying the stencil sheet, means for raising and lowering said frame, an ink and presser roller carrying a pinion, a lever pivoted at one end and having teeth upon its upper and lower edges 120 to be engaged by said pinion and spring pressed at the opposite end, and means for passing said pinion beneath said lever on its forward stroke to press the roller against the stencil sheet and for causing said roller to 125 ride upon the lever on its backward stroke to prevent the blurring of the printed sheet; substantially as described.

2. In a stencil duplicating machine, the combination with the ink and presser roller 130 carrying a pinion, of the lever pivoted at one end and spring-pressed at the opposite end

and provided upon its upper edge with teeth for the engagement of said pinion on the return stroke; substantially as described.

3. In a stencil duplicating machine, the combination with the ink and presser roller carrying a pinion, of the lever pivoted at one end and spring pressed at the opposite end, provided on its edges with teeth for the engagement of said pinion; substantially as described.

4. In a stencil duplicating machine, the combination with the ink and presser roller, of the arms L, one at each end of the roller and carrying slots with which pins on the roller are adapted to engage, the driven gear wheel K carrying the crank pin K², and the connecting rod K³ connecting said crank pin

with the ends of said levers L, and means for periodically raising said gear wheel K out of engagement with the driving gear, substantially as described.

5. The combination with the ink roller of the pivoted lever L, the gear wheel K mounted upon shaft K' and connected with lever L by means of rod K³, an arm O adapted to be periodically raised to move gear wheel K out of engagement with the driving gear, substantially as described.

In witness whereof I hereunto subscribe my name this 1st day of April, A. D. 1895.

NELLIE PARK ANDERSON.
